UNITED STATES PATENT OFFICE.

FRANCOIS VATHE, OF NEW YORK, N. Y.

GROTESQUE DOLL.

Application filed August 8, 1921. Serial No. 490,471.

To all whom it may concern:

Be it known that I, FRANCOIS VATHE, a citizen of the United States, residing at New York, in the county of New York and 5 State of New York, have invented certain new and useful Improvements in Grotesque Dolls, of which the following is a full, clear, and exact description.

An object of this invention is to provide 10 a doll which is highly amusing to both children and adults, which can be caused to assume an almost endless variety of amusing positions, and which is non-breakable and exceptionally simple and inexpensive. Other 15 objects and advantages will be apparent from the following description and the novel features will be particularly pointed out in claims.

The invention contemplates the provision 20 of a figure having grotesque features and garb with greatly elongated limbs, preferably flexible and unarticulated. This figure when disposed in almost any position will have a very grotesque and amusing appearance.

In the accompanying drawing;

Fig. 1 is an elevation of a doll constructed in accordance with the invention,

Fig. 2 is a side elevation of the same,

30 Fig. 3 is an elevation of the same when placed in one grotesque position, and

Fig. 4 is a fragmentary sectional elevation through one of the joints between a limb and the trunk.

35 In the illustrated embodiment, the doll comprises a trunk or body 1, having secured thereto a head 2 with grotesque features and a turban 3, and very greatly elongated, unshaped arms 4 and legs 5. A breech-cloth 40 6 may be secured to the trunk by a waist band 7. The entire body of the doll is formed of cloth cut and sewn to the desired shape, filled with cotton, felt, wool or other soft flexible material, the cloth form at the 45 junction of each of the limbs with the body being preferably stitched together in a line, without filling at the stitched points, as shown in Figs. 1, 2 and 4, so as to provide hinge joints. The limbs are elsewhere preferably unarticulated so as to permit of placing of the same in various and numerous 50 amusing positions with respect to the trunk and head, one of which positions is shown in Fig. 3. A small tape 8 may be attached 55 to the back at the shoulders and to the rear of the head so as to prevent the head from

falling too far forward, and may also extend slightly further as a loop 9 by means of which the doll can be suspended when desired. A doll constructed in accordance 60 with this invention is non-breakable, durable and inexpensive.

By the expressions "abnormally long," and "greatly elongated," as used in the claims in defining the length of the limbs, I 65 mean that they have a length at least one and one-half that of the average normal length of limbs relatively to the height of the person, whereby the legs can be flexed into different grotesque positions and be held 70 in those positions by interlocking them with one another or with other parts of the body without the use of hooks or other fastening means.

It will be obvious that various changes 75 in the details herein described and illustrated may be made by those skilled in the art within the principle and scope of the invention.

I claim:

1. A doll comprising a trunk, a head with grotesque features, and very abnormally long flexible limbs whereby the limbs can be placed and held in various grotesque positions without the use of fastening means. 80

2. A doll comprising a grotesque figure with very abnormally long flexible limbs whereby the limbs can be placed and held in various grotesque positions without the use of fastening means. 85

3. A doll comprising a figure with greatly elongated, unshaped flexible limbs whereby the limbs can be placed and held in various grotesque positions without the use of fastening means. 90

4. A doll comprising a figure with greatly elongated flexible legs whereby the limbs can be placed and held in various grotesque positions without the use of fastening means. 95

5. A doll comprising a figure with grotesque features and greatly elongated flexible unarticulated legs whereby the limbs can be placed and held in various grotesque positions without the use of fastening means. 100

6. A doll comprising a figure with grotesque features and greatly elongated legs whereby the limbs can be placed and held in various grotesque positions without the use of fastening means. 105

7. A doll comprising a fabric form filled with soft flexible material, the limbs being 110

- greatly elongated to give the form a grotesque appearance whereby the limbs can be placed and held in various grotesque positions without the use of fastening means.
5. 8. A doll comprising a fabric form filled with soft flexible material, the limbs being greatly elongated to give the form a grotesque appearance, the fabric at the junction of the limbs and trunk being stitched together without filling to provide a hinge joint whereby the limbs can be placed and held in various grotesque positions without the use of fastening means.
10. 9. A doll comprising a fabric form filled with soft flexible material, the limbs being unarticulated, flexible and greatly elongated

to give a grotesque appearance whereby the limbs can be placed and held in various grotesque positions without the use of fastening means.

20. 10. A doll comprising a fabric form filled with soft flexible material, the limbs being unarticulated, flexible and greatly elongated to give a grotesque appearance, the fabric at the junction of the limbs and trunk being stitched together without filling to provide a hinge joint whereby the limbs can be placed and held in various grotesque positions without the use of fastening means.

25. In witness whereof, I hereunto subscribe my signature.

FRANCOIS VATHÉ.
